Patented Dec. 25, 1973

229,675

POURING SPOUT FOR A PAINT CAN OR THE LIKE

Frank Kuncz, Jr., 2453 Roberta St., Largo, Fla. 33540

Filed Apr. 21, 1972, Ser. No. 251,605

Term of patent 14 years

Int. Cl. D9—07

U.S. Cl. D9—290

FIG. 1

FIG. 2

FIG. 3

FIG. 4

FIG. 5

FIG. 6

FIG. 1 is a top plan view of a pouring spout for a paint can or the like showing my new design.

FIG. 2 is a front elevational view.

FIG. 3 is a left side elevational view.

FIG. 4 is a right side elevational view.

FIG. 5 is a bottom plan view.

FIG. 6 is a fragmentary cross-sectional view taken along the line 6—6 of FIG. 1 and on an enlarged scale.

I claim:

The ornamental design for a pouring spout for a paint can or the like, as shown.
